UNITED STATES PATENT OFFICE

MORRIS SALSBERG, OF SCRANTON, PENNSYLVANIA

WINDOW SCREEN

Application filed December 30, 1930. Serial No. 505,622.

My invention relates to new and useful improvements in window screens and has for its principal object the provision of a screen which will be attached to the window sash and operable therewith, the screening being unwound from a roller as the sash is moved into open position, to cover the opening caused by the opening of the window, the screening being rewound upon the roller as the sash is moved into closed position.

A further object of the invention consists in the provision of novel forms of casings or housings in which the rollers for the screening are mounted and novel means for securing or mounting the housing or casings within the window frame.

With the above and other objects in view, which will appear as the description proceeds, my invention consists in the novel details of construction, and arrangement of parts, described in the following specification and illustrated in the accompanying drawings, and while I have illustrated and described the preferred embodiments of the invention, as they now appear to me, it will be understood that such changes may be made as will fall within the scope of the appended claims.

In the drawings:—

Fig. 1 is a front elevation of a window frame and sashes operable therein with my improved form of screen in position.

Fig. 2 is a vertical section through the construction shown in Fig. 1.

Fig. 3 is a horizontal section on the line 3—3 of Fig. 2.

Fig. 4 is a horizontal section on the line 4—4 of Fig. 2.

Fig. 5 is a fragmental longitudinal section through the lower casing or housing with parts of the roller containing the screening in elevation and part in longitudinal section.

Fig. 6 is an end view of the lower casing or housing.

In the drawings 1 indicates the window frame, 2 the lower sash, and 3 the upper sash all of usual and well-known construction, the sashes being adapted for sliding movement within the frame. At 4 I have ill-

lustrated what may be termed the lower casing or housing adapted to be mounted in the lower end of the frame, the casing or housing being formed at one end with the closure 5 and upwardly extending flange 6 adapted to be engaged by the clamping plate 7 which is secured to the side of the frame by means of the screws 8 or other suitable fastenings. The opposite end of the casing or housing is of open formation and has an upwardly extending flange 9 and a corner portion 10 adapted to be engaged respectively by the inwardly turned flange portions 11 and 12 of a plate 13 which will close a portion of the open end of the casing or housing as shown more particularly in Fig. 6 of the drawings. It will be understood that this plate 13 may be engaged with or removed from the end of the casing or housing by sliding movement. A clamping plate 14 is secured to the side of the frame 1 by means of the screws 15 or other suitable fastenings and, as shown more particularly in Fig. 5 of the drawings, overlies and engages the inturned flange 11 which in turn, as previously stated, is engaged with the upwardly directed flange 9 formed on the end of the casing or housing.

Mounted within the casing or housing 4 is a roller 16 upon which the screening 17 is adapted to be wound it being understood that the roller 16 is spring controlled similar to the well-known form of window shade roller. A projection 18 is formed on one end of the roller and is normally received in an opening 19 formed in the closed end of the casing or housing 4. A spindle 20 extends into the opposite end of the roller, as shown more particularly in Fig. 5 of the drawings, and surrounding this spindle is a coiled spring 21 having its inner end 22 secured to the spindle and its opposite end 23 connected to a cap 24 forming a closure for the end of the roller. The outer end 25 of the spindle is of elongated formation, as shown more particularly in Fig. 6 of the drawings and is adapted to be engaged in a notch or recess 26 formed in the edge of the plate 13. With this construction when the screening is unwound from the roller the spring 21 will be

placed under tension and operate the roller to rewind the screening thereon when the screening is released. The casing or housing 4 is provided, at the back, with an elongated opening 27 through which the screening may be withdrawn as shown more particularly in Fig. 6 and the end of the screening is secured to a metal strip 28 which is formed with openings through which may extend the screws 29, or other suitable fastenings, for securing the strip with the screening to the lower sash 2. It will be seen that by removing the screws 29 that the screening may be detached from the sash so that when desired, such as in winter time, the sash may be operated independently of the screen. At the same time, when desired, the entire casing or housing 4 may be removed from the frame by an outward sliding movement relative to the clamping plates 7 and 14. The screening 17 may be of any desired form such as wire or cloth although for the purpose of illustration I have shown the cloth of such mesh as to allow ventilation when the sashes are raised or lowered into open position but preventing the entrance of flies or other insects.

Secured to each side of the frame 1, at the lower portion and extending to the top of the lower sash 2 when the sash is in its normal lowered position are the guideways indicated generally at 34. These guideways are formed of metal bent to form the attaching portion 35 and spaced arms 36 and 37 extending at right angles relative to the attaching portion. The attaching portions of the guideways are formed with the slots 38 terminating at one end in the enlargements 39 of a size to permit the entrance of the heads of the screws 40 which secure the guideways to the frame. It will be understood that in applying the guideways to the frame that they will be positioned to allow the heads of the screws 40 to pass through the enlarged ends 39 of the slots 38 and then by sliding the guideways downward the screws will pass into the slots 38. Preferably the screws will be tightened to securely hold the guideways in position. The ends of the strip 28 as well as the edges of the screening 17 are adapted to operate in the guideways between the arms 36 and 37 thereof as shown more particularly in Fig. 3 of the drawings.

At 41 I have shown what might be termed the upper casing or housing which is positioned within the frame 1 at the top as shown more particularly in Fig. 2 of the drawings. At each end the casing or housing 41 is provided with an outwardly directed flange 42 through which a screw 43 will be passed for securing the casing or housing within the frame. The casing or housing is closed at one end, the same as the lower casing, and normally open at the opposite end. The normally open end will be closed by a plate similar to the plate 13, this plate being pro-

vided with the inturned flanges 44, shown in Fig. 2, which engage the flange 42. Mounted within the casing or housing, in the same manner as the roller 16 is a spring controlled roller 45 to which is secured and wound the screening 46, this screening passing through an opening 47 formed in the casing or housing. Secured to the outer edge or end of the screening 46 is the metal strip 48 which is adapted to be secured to the top of the upper sash 3 by means of the screws 49 or other suitable fastenings.

Secured to the sides of the frame 1 and normally extending to a point adjacent the lower edge of the sash 3 are the guideways 53. These guideways are of what may be termed C-formation with their closed vertical edges embedded within the sides of the frame, as shown more particularly in Fig. 4 of the drawings, and forming a continuation of the parting strips 54. In other words the parting strips 54 do not extend above the lower sash and the guideways 53 form continuations of the parting strips 54 and take the place of the parting strips normally used adjacent the upper sash. The guideways at their inner open edges are formed with the inwardly directed integral arms 55, spaced as shown in Fig. 4 to receive the ends of the strip 48 and the edges of the screening 46. Preferably the guideways 53 are sufficiently resilient to be held within the recesses of the frame by friction but, if desired, screws or other fastenings may be used for securing them to the frame. The inwardly directed arms 55, if desired, may be spaced a sufficient distance apart to allow free movement of the ends of the strip 48 or to frictionally engage the same.

From the above detailed description it is thought that the construction and operation will be clearly understood. It will be seen, as stated in the objects of the invention, that I have provided novel forms of casings or housings for receiving the rollers upon which the screening is wound, novel means for connecting the casings or housings to the window frame, and novel forms of guideways for the edges of the screening as well as the ends of the strips which secure the ends of the screening to the sashes. With the ends of the screening secured to the sashes when the sashes are moved into open position the screening will be unwound from their respective rollers and then when the sashes are returned to their normally closed positions the screening will be rewound upon the rollers. When desired the ends of the screening may be detached from the sashes to allow operation of the sashes independently of the screens.

Having fully described my invention what I claim as new and desire to secure by Letters Patent is:

1. A housing mounted in a window frame,

a flange formed on each end of the housing, and clamping plates detachably connected to the window frame and engageable with the flanges for securing the housing within the frame.

5 2. A window screen device including a roller housing normally closed at one end and open at the opposite end, a plate detachably connected to one end of the housing for partially closing the normally open end.

10 3. A window screen device including a housing normally closed at one end and open at the opposite end, a flange formed on each end of the housing, a plate having portions 15 cooperating with the flange on the open end of the housing for detachably connecting the plate to the housing and partially closing the normally open end, and means engageable with the flanges for securing the housing 20 within a window frame.

25 4. A window screen device including a housing, normally closed at one end and open at the opposite end, a flange formed on each end of the housing, a plate having inturned flanges 30 cooperating with the flange on the open end of the housing for detachably connecting the plate to the housing and partially closing the normally open end, and means engageable with the flanges for securing the housing within a window frame.

35 In testimony whereof I hereunto affix my signature.

MORRIS SALSBERG.
